UNITED STATES PATENT OFFICE

JAMES J. HAUSER, OF NEW YORK, N. Y.

FUEL INJECTOR NOZZLE FOR INTERNAL COMBUSTION ENGINES

Application filed June 20, 1931. Serial No. 545,652.

My invention relates to nozzle structures for use in internal combustion engines of the Diesel type and it is my object to regulate the rate of injection of the fuel oil by simple and efficient means. By "rate" I mean the total quantity of fuel oil going into the cylinder in unit time.

By the use of my improved nozzle the injection of fuel oil can be so regulated that lower maximum cylinder pressures, higher brake mean effective pressures and lower fuel consumption can be obtained.

The nozzle is adaptable for use with internal combustion engines of any cycle and with any fuel and can be used either as a dual or multiple nozzle.

I employ a primary jet which is coarse and of restricted area so that a small amount of fuel can be introduced into the combustion space to start local combustion, which might represent idling conditions of the engine. I also employ secondary and later operating jets which give a fine spray with rapid distribution of the fuel whereby quick combustion is assured so that operating conditions of high efficiency are obtained during that portion of the expansion stroke of the piston during which these conditions are highly desirable.

In the drawings Fig. 1 is a sectional view of my invention embodied in a dual orifice nozzle; Fig. 2 a top view of the structure of Fig. 1; and Fig. 3 a view of a pair of pistons and valves for use in a slightly modified form of nozzle in which the effective pressure area of the pistons is obtained by differences in the diameter of the valve stems.

In the form shown my improved nozzle consists of a body 1 having a plurality of chambers 2 and 3 therein, which are preferably circular in cross-section, the cross-sectional area of the chamber 2 being preferably greater than that of the chamber 3. A fuel oil passage 4 connects with both of these chambers. Each chamber preferably has an open, threaded upper end to receive the plugs 5 and 6 for a purpose hereinafter explained.

Each chamber has a nozzle orifice, 7 and 8, at its lower end. I prefer to make the shape and size of the orifice 7 in the chamber 2 such that a small, concentrated stream of

fuel oil will be injected therethrough while the size and shape of the orifice 8 in the chamber 3 is such that the fuel oil injected therethrough will be larger and more diffused than that ejected by the orifice 7.

In each cylinder or chamber I fit a piston, 9 and 10, which is a sliding fit. As shown in the drawings I prefer to counterbore the head of each piston at 11 and 12. Each piston is provided with a valve stem, 13 and 14, which terminates in a valve, 15 and 16, engaging the inner ends of the orifices 7 and 8 to open and close the same.

In the form shown I have placed a spring, 17 and 18, in the counterbores of the cylinders and close the upper ends of the chambers or cylinders with the screw plugs 5 and 6 so that by screwing these plugs in or out the springs will be more or less compressed thus varying the pressure required to lift the valves 15 and 16 off their seats to permit the ejection of fuel oil through the orifices 7 and 8 during the injection stroke of the fuel pump (not shown).

Instead of two chambers with their associated parts I may employ any number more than one.

The body 1 is preferably provided with a flange 19, or other means for securing the nozzle to a cylinder head with the orifices within the cylinder and in the combustion space.

In operation the injection pump will force the fuel oil through the oil passage 4 and fill both chambers 2 and 3 below the pistons. As the pressure on the fuel oil rises under the continued movement of the pump and the restricted outlet of the nozzle resisting the flow the piston 9 will lift first, due to its larger effective area and lift the valve 15 off its seat permitting a small, concentrated jet of fuel oil to enter the combustion space in which the air charge has been compressed on the up stroke of the engine cylinder. This small jet of injected oil begins to burn and pressure is applied to the engine piston. After this burning has begun the increased oil pressure in the chambers 2 and 3 causes the piston 10 to lift and raise the valve 16 off its seat permitting fuel oil to be injected into

the already burning mixture of air and oil and progressively building up the pressure in the engine cylinder so that maximum efficiency is obtained without high initial pressures while the engine piston is approximately at top dead center.

The successive action of the jets may be obtained in a number of ways. For example, the cylinders and pistons in the nozzle may 10 be of the same diameters and the valve stems 13' and 14' of different diameters as shown in Fig. 3, thus varying the piston surface exposed to pressure of the fuel oil.

By this construction I start the burning 15 by injecting a small amount of fuel oil through the primary orifice and thereafter inject the main charge of fuel oil through the secondary orifice into the already burning mixture.

20 I claim:—

1. A fuel injector nozzle for internal combustion engines comprising a body, a plurality of chambers therein provided with orifices at their lower ends, a fuel oil passage 25 through said body communicating with said chambers, a piston in each chamber, a valve on each piston adapted to open and close the chamber orifice, the effective cross-sectional areas of said pistons being different whereby 30 they will successively lift under fuel oil pressure in the chambers.

2. A fuel injector nozzle for internal combustion engines comprising a body, a plurality of chambers therein provided with orifices at their lower ends, the orifice in one chamber giving a small, concentrated discharge and the orifice in the other chamber giving a large, diffused discharge, a fuel oil passage through said body communicating 35 with said chambers, a piston in each chamber, a valve on each piston adapted to open and close the chamber orifice, the effective cross-sectional area of the piston operating on the small discharge orifice being greater than 40 the effective cross-sectional area of the piston in the chamber having the large discharge orifice whereby they will successively lift under fuel oil pressure in the chambers.

3. A fuel injector nozzle for internal combustion engines comprising a body, a plurality of chambers therein provided with orifices at their lower ends, a fuel oil passage 50 through said body communicating with said chambers, a piston in each chamber, a valve on each piston adapted to open and close the chamber orifice, means for adjusting the pressure of the valves on their seats, the effective cross-sectional areas of said pistons being 55 different whereby they will successively lift 60 under fuel oil pressure in the chambers.

4. A fuel injector nozzle for internal combustion engines comprising a body, a plurality of chambers therein of different cross-sectional areas and provided with orifices at 65 their lower ends, a fuel oil passage through

said body communicating with said chambers, a piston in each chamber, a valve on each piston adapted to open and close the orifices, a spring bearing on the upper side of each piston and a screw plug in the body bearing 70 on each spring whereby the pressure on the valve on its seat may be adjusted.

In testimony whereof I have affixed my signature.

JAMES J. HAUSER. 75
